TRIMMING.

No. 18,952.

Patented Mar. 12, 1889

UNITED STATES PATENT OFFICE.

JOHANN C. F. EDELMANN AND ALPHONSE H. KURSHEEDT, OF NEW YORK,
N. Y., ASSIGNEES TO THE KURSHEEDT MANUFACTURING COMPANY, OF
SAME PLACE.

DESIGN FOR TRIMMING.

SPECIFICATION forming part of Design No. 18,952, dated March 12, 1889.

Application filed January 21, 1889. Serial No. 297,102. Term of patent 7 years.

To all whom it may concern:

Be it known that we, JOHANN C. F. EDELMANN and ALPHONSE H. KURSHEEDT, both of the city, county, and State of New York, have 5 invented and produced a new and original Design for Dress-Trimming, of which the following is a specification, reference being had to the accompanying photograph, forming part hereof, which is a face view of our newly-10 designed dress-trimming.

The leading features of our design consist, first, of a fanciful leaf having a rosette and sprays and tendrils; second, of a border having a reticulated filling and a trefoil, and, 15 third, of a fanciful leaf, having a rosette, sprays, and tendrils, and of a border having a reticulated filling and a trefoil.

In the accompanying photograph, A represents a fanciful leaf, within which is a rosette, 20 a, and sprays b. Tendrils d extend from the

leaf A. The border B has a reticulated interior filling, f, and trefoils g.

We claim—

1. The design for a dress-trimming, consisting of the fanciful leaf A, having the rosette a and sprays b, and the tendrils d, substantially as shown. 25

2. The design for a dress-trimming, consisting of the border B, having reticulated filling f and trefoil g, substantially as shown. 30

3. The design for a dress-trimming, consisting of the fanciful leaf A, having rosette a, sprays b, and tendrils d, and of the border B, having reticulated filling f and trefoil g, substantially as shown. 35
